Robert I. McNaughton,
Inventor

By *Geo. P. Kimmel*

Attorney

UNITED STATES PATENT OFFICE.

ROBERT I. McNAUGHTON, OF MINOT, NORTH DAKOTA.

SACK-HOLDER.

1,312,336.

Specification of Letters Patent. Patented Aug. 5, 1919.

Application filed November 12, 1918. Serial No. 262,183.

To all whom it may concern:

Be it known that I, ROBERT I. McNAUGHTON, a citizen of the United States, residing at Minot, in the county of Ward and State 5 of North Dakota, have invented certain new and useful Improvements in Sack-Holders, of which the following is a specification.

This invention relates generally to improvements in devices for bagging grain, 10 etc., and more particularly has reference to an improved sack holder.

It is the principal aim and object of the present invention to provide a device of the above mentioned character designed for supporting a sack or bag and for holding the hemmed mouth thereof in an extended position while grain or the like is being placed into the same while the component parts of the holder are of novel construction and are 15 capable of being moved relative to each other for insuring of the removable clamping of the sack in position and at the same time the parts are relatively adjustable so that various sized sacks may be clamped in 20 a supported position.

More particularly this invention consists in the provision of a device of the above mentioned character wherein clamps of improved construction are mounted on the vertically adjustable main support and designed to coöperate with the supporting yoke or bail in such a manner that the yoke or bail may be removed therefrom when it 25 is not desired to use the device; swung into a raised position relative thereto to permit of the clamping of the bag or sack in the proper position; and also slid to insure of the proper clamping of sacks of various sizes.

It is a more specific object of the present invention to provide a device of the above mentioned character wherein improved resilient means is designed to coöperate with the clamping bracket and the adjacent portion 40 of the bail or yoke for frictionally retaining the bail or yoke in an adjusted position.

Among the other aims and objects of the present invention may be recited the provision 45 of a sack holder of the above mentioned character wherein the number of parts are comparatively few, the construction simple, the cost of production low and the efficiency high.

The improvements in the details and arrangement of parts will be apparent from

an inspection of the accompanying drawings, in connection with the specific description hereinafter contained, and wherein the preferred embodiment of the invention is 60 disclosed for the purpose of imparting a full understanding of the invention.

The invention is clearly illustrated in the accompanying drawings, in which:

Figure 1 is a perspective view of the 65 holder showing a sack clamped in a supported position,

Fig. 2 is a perspective detail of one of the clamps,

Fig. 3 is a vertical longitudinal sectional 70 detail through one of the clamps,

Fig. 4 is a rear elevational detail of one of the clamps.

Similar characters of reference are employed in all of the above described views, 75 to indicate corresponding parts.

Referring now, more particularly, to the accompanying drawings, there is provided a standard 1 to which is adjustably connected for vertical movement a cross bar 2, connection being preferably maintained between the bar and the standard through the instrumentality of a bracket 3 which is secured to the bar by suitable fasteners 4 and designed to slide vertically on the standard 80 85 and held in various positions of adjustment thereon by fasteners 5 which removably engage the bracket and standard and consequently support the bar.

With a view toward providing the improved clamping means there is employed a pair of brackets each indicated in its entirety by the numeral 6. In the present instance, each clamp or bracket may be said to consist of a body 7 of a plate-like form 95 provided in its upper surface with a longitudinally extending groove 8 preferably curved transversely at the bottom for a purpose that will presently appear. Spaced jaws 9 and 10 depend from the body, the front jaw 9 alining with the front or inner edge of the body while the outer jaw is slightly longer and is formed with an opening 11 through which is passed a fastener, such as a clamping screw 12 also designed to 105 be anchored in the cross bar when the legs are straddled thereabout, thereby insuring of the removable clamping of the bracket with the cross bar. Spaced parallel arms 13 project rearwardly from the body and aline 110 with the side edges thereof being joined at their outer ends by an arch 14, preferably

integral therewith and this arch, the arms and the body 7 form an opening 15 for a purpose which will presently appear. The rigidity of the arms is increased by means 5 of the integral braces 16 which are preferably joined with the under surfaces of the arms and the adjacent faces of the jaw 10 at the sides thereof. It is also to be noted that the inner edge of the body 7 is formed 10 with an inwardly extending slot 17, which leads from the opening 15, for a purpose which will presently appear. Coöoperating with the brackets 6, which are clamped on the bar 2 at opposite sides of the standard 1, is 15 the sack supporting yoke or bail generally designated by the numeral 18 and preferably of a U-shaped configuration including an intermediate portion 19 and spaced side portions or arms 20. The outer extremities of 20 the side portions are designed to be arranged through the openings 15 in the brackets 6 and in clamping the sack or bag 21 the upper hemmed edge is stretched across the cross bar and the body of the clamping 25 bracket being engaged by the opposed longitudinal series of pointed lugs 22 formed on the upper face of each body 7 and preferably near the side edges. When in such position, the bail or yoke is in a raised position and has its intermediate portion 19 30 engaged against the inner surface of the mouth of the sack beneath the hem thereof. In finally securing the sack, the yoke is swung outwardly and downwardly and slid 35 forwardly the desired extent so that the portions of the sack lying above the recesses 8 will be clamped between the recesses 8 and the side portions 20 of the yoke. Co-acting with the side portions of the yoke are 40 resilient members in the form of leaf springs 23, each of which is preferably right angular in form and consists of an attaching portion 24 and a resilient portion 25. In arranging the springs in position, the attaching or anchoring portion 24 is arranged in 45 the adjacent slot 17 and clamped between the jaw 10 and the cross bar as indicated in Fig. 3, while the resilient portion is positioned between the arms 13 and tensioned 50 toward the arch 14 so as to exert its tension on the adjacent side portions 20 of the yoke and thereby frictionally engage and retain the said side portions against accidental sliding movement. These springs however, do 55 not prevent manual sliding adjustment of the side portions so that various sized bags may be clamped and held in a supported position by the device.

It is believed in view of the foregoing

description that a further detailed description of the operation of the invention is entirely unnecessary. Likewise, it is believed that the advantages of the invention will be readily apparent.

Still further embodiments of the invention than those herein especially defined may be resorted to as conditions or preference may dictate, as may be in keeping with the hereto appended claims.

Having thus fully described my invention, 70 what is claimed as new and desired to be secured by Letters Patent, is:

1. The combination with a support including a cross bar, of a U-shaped carrier having its arms extending across the cross bar, 75 and clamps connecting the arms of the carrier with the cross bar, said clamps each comprising side arms extending in spaced relation, spaced jaws depending from the side arms upon opposite sides of the cross bar and connecting the side arms, a bridge connecting the outer ends of the side arms, and a resilient strip extending between the cross bar and one of said jaws and having its free end portion bent to extend between the side 80 arms, the resilient strip of the clamps engaging the side arms of the carrier to hold the same in engagement with the bridges.

2. The combination with a support including a cross bar, of a carrier having side 90 bars extending across the cross bar, and means for connecting the side bars of the carrier with the cross bar, said means each comprising a body structure connected with the cross bar and having side arms extended 95 outwardly therefrom in spaced relation, a bridge connecting the outer end portions of the side arms, the side bars of the carrier extending between the side arms of the connecting means and beneath the bridges thereof, and resilient strips extending from the body structure of the connecting means between the arms thereof and engaging the side bars of the carrier to hold the same in engagement with the bridges.

3. A clamp for the purpose described, comprising a body structure having depending support engaging jaws, side arms extending from the body structure in spaced relation, a bridge connecting the outer end 100 portions of the side arms, and a resilient strip extending from the body structure between the side arms for engaging an article extending between the side arms and holding the same in engagement with the bridge.

In testimony whereof, I affix my signature hereto.

ROBERT I. MCNAUGHTON.
